[57] CLAIM

The ornamental design for a jug handle holder, as shown and described.

DESCRIPTION

FIG. 1 is a front perspective view of a jug handle holder showing our new design;

FIG. 2 is a rear perspective view thereof;

FIG. 3 is a front elevational view thereof;

FIG. 4 is a rear elevational view thereof;

FIG. 5 is a right side elevational view thereof;

FIG. 6 is a top plan view thereof;

FIG. 7 is a bottom plan view thereof; and,

FIG. 8 is a perspective view illustrating the holder attached to handles of two conventional jugs.

The broken line showing of two jugs is for illustrative purposes only and forms no part of the claimed design.
